CLAIM

The ornamental design for an attachment for a hand mixer, as shown and described.

DESCRIPTION

FIG. 1 is a perspective view of an attachment for a hand mixer showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof; and,

FIG. 7 is a front elevational view thereof.

The broken line showing of a mixer housing and beaters in FIGS. 1-7 are environmental only and form no part of the claimed design.

FIG. 1FIG.2FIG. 3FIG.4FIG. 5FIG.6FIG.7
